EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

SHIFT-KEY MECHANISM FOR TYPE-WRITING MACHINES.

1,226,770.

Specification of Letters Patent.

Patented May 22, 1917.

Application filed August 24, 1916. Serial No. 116,604.

To all whom it may concern:

Be it known that I, EDWARD B. HESS, a citizen of the United States, residing in Brooklyn, in the county of Kings and State of New York, have invented certain new and useful Improvements in Shift-Key Mechanism for Type-Writing Machines, of which the following is a specification.

This invention relates to the mechanism of typewriting machines for effecting changes in the letter case printing, and particularly to mechanism of this class in which a key lever is employed for shifting the platen or carriage from lower to upper case position. Usually when the shift key is depressed it comes to a full stop suddenly as soon as the carriage is shifted and the touch of the key is therefore hard and rigid, differing in these respects from the other keys in the key board.

The object of this invention is to provide means for giving a soft and easy touch to the shift key, and this I do by providing the shift key mechanism with cushioning devices which are of such construction and which are so associated with the shifting mechanism that the shift key may be moved in the usual way and to the usual extent to effect the shifting from lower to upper case, and may then have an additional movement under a yielding strain.

My improvements may be applied to various forms of typewriting machines equipped with different kinds of mechanism for shifting the carriage or otherwise changing the letter space printing.

In the accompanying drawings, I have shown one way of carrying out my invention as applied to a Royal standard machine.

Figure 1 is a diagrammatic side view, showing such portions of the shift mechanism as are necessary to illustrate my invention.

Fig. 2 is a detail view on an enlarged scale of the cushioning devices interposed between the shift key and the carriage-lifting mechanism.

The carriage A supports a platen B and is supported at its front on a shift rail C which has downwardly extending arms D, connected at their lower ends to parallel links E, pivoted to the machine frame at e. Levers F are pivotally connected to the arms D near their upper ends and the rear ends

of these levers are pivotally connected with 55 the machine frame at f. G indicates a latch for locking the carriage in lower case position. When the carriage is lowered the latch G engages a lug d on one of the arms D. It will be understood that there is a 60 pair of links E and a pair of levers F, those on one side of the machine only being shown.

The shift lever H is pivoted at h to the machine frame and carries a finger key h'. A shift locking lever and key I and locking 65 devices J are associated with the shift lever in the usual way. Said lever H is in the bell-crank form and is connected by a rod K with the locking latch G in the usual way and it is connected with one of the levers F 70 by rods, associated with adjusting and cushioning devices of novel construction.

It will be understood that more than one shift lever and more than one locking lever may be used in the usual way.

A rod L is connected with the lower end of one of the levers F and another rod M is connected with the bell-crank lever H. The connection between the rod L and the lever F is preferably made by forming a loop a 80 on the rear end of the rod which engages a pin f' on the lever, and this loop at its front end is connected with a spring g which is attached at its rear end to the pin f'. When the carriage is elevated the spring g is under 85 tension as indicated in Fig. 1, but when the carriage is lowered the spring causes the rear end of the loop to separate from the pin a short distance so that when the shift lever is again depressed there is a little lost motion before the rear end of the loop engages the pin f' and thus before the raising of the carriage commences. In this way time

is given for the latch G to be disengaged from the carriage before the latter commences to rise. Between these two rods the adjusting and cushioning device N is interposed. The rod M is adjustably connected at its front end with a plug m screwed into the rear end of a tube 100 m' and held in its adjusted position by a nut m'. The rod L enters an internally threaded sleeve l and is adjustable therein, being held in adjusted position by a nut l'. The sleeve l enters the tube m' and is 105 formed at its inner end with a head l'. Between the head l' of the sleeve l and the front end of the tube is interposed a spring

O placed under compression and tending to move the rod L rearward or to press the tube forward.

When a shift key is depressed it at first 5 draws the rods L and M and their connections forward and raises the carriage to its full extent against a stop S and without putting further compression on the spring, but the shift key may then be further de- 10 pressed and the spring O is put under compression and thus acts as a cushion to the operation of the shift key. When the shift key is released the compression of the spring is relaxed and the parts return to 15 their normal condition in the usual way.

My invention is not limited to the details 20 of construction illustrated and may be applied to machines of various kinds constructed to effect the shifting from lower case to upper case printing in various ways, the essential feature of the invention being 25 the provision of means substantially such as described for permitting the shift key to operate in the usual way to effect a change from lower to upper case printing and to then have a further movement which is in some suitable way cushioned to afford an easy touch.

I claim as my invention:

30 1. In case-shifting mechanism for typewriting machines, a stop for limiting the movement of the part to be shifted, a pivotally mounted shift key lever, and connections between the lever and the part to be shifted in which are interposed, between the part to be shifted and the lever, yielding means adjusted to be normally ineffective during the initial movement of the lever but which yield in order to cushion the movement of the lever after the shifted part 35 has been moved to its full extent against its stop.

40 2. In case-shifting mechanism for typewriting machines, a stop for limiting the movement of the part to be shifted, a pivotally mounted shift key lever, and connections between the lever and the part to 45

be shifted in which are interposed, between the part to be shifted and the pivot of the lever, yielding means adjusted to be normally ineffective during the initial movement of the lever but which yield in order to cushion the movement of the lever after the shifted part has been moved to its full extent against its stop. 50

55 3. In case-shifting mechanism for typewriting machines, a shift key lever, a stop for limiting the movement of the part to be shifted, and connections between the shift key lever and the part to be shifted having a yielding portion interposed between the rear end of the lever and the part to be shifted which is normally adjusted to permit the shifted part to be moved to its full extent against its stop without materially yielding and which thereafter yields to permit the shift key lever to be further depressed while being thus cushioned. 60

4. The combination with an adjustable typewriter carriage of a stop for limiting its movement, a pivoted shift key lever, and 70 connections between the lever and the carriage whereby the latter may be moved firmly against its stop and which are provided with yielding devices interposed between the pivoted portion of the lever and the carriage which are adjusted to cushion the movement of the lever after the carriage is moved to its full extent against its stop. 75

5. The combination with a shift key and 80 a shift rail of a typewriting machine, of a rod connected with the shift key, a tube to which said rod is adjustably connected, a sleeve within said tube, a rod adjustably connected with said sleeve and operatively 85 connected with the shift rail, and a spring within the tube for holding said sleeve yieldingly therein.

In testimony whereof, I have hereunto 85 subscribed my name.

EDWARD B. HESS.
